Attorneys.

UNITED STATES PATENT OFFICE.

HARRY V. ASHBY, OF ERIE, PENNSYLVANIA.

MATCH-HOLDER.

1,364,231.

Specification of Letters Patent.

Patented Jan. 4, 1921.

Application filed February 7, 1920. Serial No. 356,891.

To all whom it may concern:

Be it known that I, HARRY V. ASHBY, a citizen of the United States, and a resident of Erie, Erie county, State of Pennsylvania, 5 have invented certain new and useful Improvements in Match-Holders, of which the following is a specification.

My invention relates to a device for holding stubs or burnt portions of used matches 10 and it consists generally of a plate which is adapted to be secured to a wall or other suitable support and which at its lower end is shaped to form a holder in which a receptacle is adapted to be placed, the holder 15 and receptacle being hinged together along one edge so that the receptacle which is intended to receive the burnt matches may be rotated about the hinge and thereby inverted to deposit its contents in any suitable 20 container, a handle being provided for moving the receptacle. This construction provides a device into which the stubs or burnt matches may be deposited and from which they may be removed without soiling 25 the hands or handling the same in any way by merely moving the handle so as to invert the receptacle. This arrangement of holder and receptacle also provides a construction which is comparatively rigid, particularly when the holder is provided with 30 ends, as hereinafter described. The entire device is simple in construction, easy to operate, and the same can be easily and cheaply manufactured.

35 With these and other objects in view, my invention consists in the matters herein set forth and included in the appended claims.

Referring to the drawings:

Figure 1 shows the front elevation of the 40 device, parts being broken away and others shown in section;

Fig. 2 is a side elevation of the device; and

Fig. 3 is a transverse section on the line 45 3—3 of Fig. 1.

Referring to the drawings in detail, A represents a plate which is adapted to be secured to a wall or other suitable object. At its lower end this plate is bent or curved 50 outwardly from the body thereof and then upwardly to form a holder for the receptacle into which the burnt matches are to be placed. Such outwardly bent and curved part comprises a bottom portion C and an 55 upstanding portion C', such portions con-

stituting the holder. The holder may also be supplied with end portions B attached to the body of the plate and to the up-turned portion C' of the holder. These end portions serve to give rigidity to the holder and 60 permit construction of the device from thin material. A receptacle D is provided which is so shaped as to fit in the holder and such receptacle is hinged along one edge to the upper edge of the upstanding portion C' of 65 the holder, as shown at E. A pivot wire F extends through the hinged connection between the receptacle and the holder, this wire being suitably secured to the receptacle D. The end of the wire beyond the hinge is 70 bent in the form of a handle G which serves as a means for tilting the receptacle about the hinge for the purpose of discharging its contents.

If desired, the plate A may be provided 75 above the holder with a receptacle (not shown) adapted to contain unused matches.

Having thus described the invention what I claim as new and desire to secure by Letters Patent is:

1. A device for containing burnt matches or the like comprising a plate bent outwardly and upwardly at one end to form a holder, a receptacle adapted to fit said holder and rest therein, said holder and receptacle being hinged together along one edge thereof, and a pivot wire extending through said hinged connection of the holder and receptacle and secured to said receptacle, one end of said wire being 85 shaped to form a handle for tilting the receptacle.

2. A device for containing burnt matches or the like comprising a plate bent outwardly and upwardly at one end to form 95 a holder, plates secured to the upturned end and the body of said first named plate and forming ends for said holder, a receptacle adapted to fit said holder and rest therein, said receptacle being hinged to the upwardly extending portion of said first named plate, a pivot wire extending through said hinged connection and secured to the receptacle, said wire extending at one side beyond the end of the holder and receptacle 100 and bent to form a handle for tilting said receptacle.

In testimony whereof I affix my signature.

HARRY V. ASHBY.
